COLLAR CAN COLLAR MOUNTING

John Coyle, Baltimore, Md., and William F. Punte, Passaic, N. J., assignors to Continental Can Company, Inc., New York, N. Y., a corporation of New York

Application July 7, 1944, Serial No. 543,858

1 Claim. (Cl. 220—54)

1

The invention relates generally to well known tear strip or collar can structures and primarily seeks to provide a novel collar structure and mounting therefor.

In the well known tear strip cans it is customary to provide a collar within the upper portion of the can in position for projecting upwardly beyond the end of the can body after the tear strip is torn out to effect an opening of the can, thereby to provide a mounting neck over which the skirt or body portion remaining attached to the top closure of the can when the tear strip is removed can be telescoped in order to effect a reclosure of the can. It is an object of the present invention to provide a novel collar structure so constructed and mounted as to accomplish the intended purpose of providing a reclosure mounting without presentation of any raw metal edge portions in position where they can be contacted by a hand of a user of the can.

In its more detailed nature the invention resides in providing a can structure of the character stated with an outwardly directed bead adjacent the upper end thereof, and a collar snugly telescoped in said upper end in position for extending above the upper end extremity of the can body provided by tearing out of the tear strip, said collar including an inwardly curled upper end extremity, an inwardly and then outwardly bent lower end extremity which is disposed within the diameter of the collar when the collar is initially inserted in the can and which during the mounting of the collar is mechanically bent outwardly into the outwardly directed can body bead so as to form a collar anchoring edge portion protected by said bead against contact by the hand of a user of the can.

With the above and other objects in view that will hereinafter appear, the nature of the invention will be more clearly understood by reference to the following detailed description, the appended claim, and the several views illustrated in the accompanying drawing.

In the drawing:

Figure 1 is a side elevation and part vertical cross section illustrating a can embodying the invention.

Figure 2 is an enlarged fragmentary vertical cross sectional view of the collar per se.

Figure 3 is an enlarged fragmentary vertical cross sectional view illustrating the collar mounting.

In the drawing the invention is illustrated as embodied in a can structure including a body 5, a lower end closure 6 and a top end closure 7.

2

The body 5 is provided with an outwardly directed bead 8 adjacent the upper end thereof, and is scored in a manner well known in the art to provide a tear strip 9 just above said bead. 5 The tear strip is so placed that when it is wound about a key in a manner well known in the art so as to be torn out of the body of the can, it will separate the main body 5 of the can from a skirt portion 10 in effecting an opening of the 10 can. The skirt portion 10 remaining attached to the top end closure 7 is disposed to be telescoped over the collar which is constructed and mounted in the novel manner hereinafter described in order to effect a reclosure of the 15 container.

The collar includes a cylindriform main body portion 11 which is snugly telescoped into the upper end portion of the body in the manner illustrated in Figures 1 and 3 so as to project above 20 the upper extremity of the body when the tear strip is removed in the manner above described. At its upper end the collar is provided with an inwardly directed curl 12, and at its lower end portion said collar is bent inwardly as at 13 and 25 then outwardly as at 14 to present a lower edge extremity which normally does not extend beyond the diameter of the main body 11. See Figure 2. It will be apparent by reference to Figure 3 of the drawing, that the juncture of the inwardly 30 and outwardly bent portions 13 and 14, respectively, of the lower portion of the collar is well rounded and spaced a considerable distance inwardly of the internal diameter of the collar main body portion so as to provide a protective shoulder effective to guard the raw metal edge extending into the can body bead 8 against contact by a 35 hand of a user of the container. In the mounting of the collar the main body of said collar is snugly telescoped into the upper end of the can body 5 and then the lower outwardly bent end extremity 14 of the collar is mechanically displaced outwardly so as to project as an anchor as 40 at 15 into the outwardly directed body bead 8. The bending of the lower end extremity of the 45 collar into the body bead 8 serves the two-fold purpose of anchoring the collar 11 in the can, and also to place the lower edge extremity of the collar in said bead in position for being protected by said extension into the bead against contact by a hand of a user of the can. The inwardly directed curl 12 at the upper extremity of the collar also assures against presentation of 50 raw metal edge portions for contact by a hand of a user of the can, and this curl additionally serves to facilitate telescoping of the closure skirt por-

tion 10 over the collar in effecting reclosure of the can.

It is to be understood that the collar herein disclosed may comprise an endless band such as would be formed from a drawn ring, or it may be shaped from a strip joined at its ends in an approved manner. An example of the last mentioned type of collar is shown in the copending application for U. S. Letters Patent Serial Number 543,655, filed by William F. Punte on July 6, 1944. When collars formed from end joined strips are employed, the joint or seam disclosed by Punte will be found desirable because in this form of joint or seam the multiple thicknesses of collar band metal are disposed only at the central cylindroform body of the collar and no overlapping of wall thicknesses is presented at the upper edge curl or the lower edge band portions of the collar.

While one form of the invention has been shown for purposes of illustration, it is to be clearly understood that various changes in the details of construction and arrangement of parts may be made without departing from the spirit

and scope of the invention as defined in the appended claim.

We claim:

5 In a sheet metal container, a body portion, an upper end closure seamed onto the body portion, said body portion having an outwardly directed bead adjacent its upper end, the body portion between said bead and the closure being scored to provide a tear strip, and a collar snugly fitting
10 the body and having a main body portion lying opposite and extending above and below the tear strip and a lower end portion bent inwardly of the main body portion of the collar and then outwardly to present a raw metal end extremity as an anchor housed in said bead, the juncture of said inwardly and outwardly bent portions being well rounded and spaced a considerable distance inwardly of the internal diameter of the collar main body portion to provide a protective
15 shoulder effective to guard said raw metal edge extremity against contact by a hand of a user of the container.

JOHN COYLE.
